(57) **CLAIM**

I claim the ornamental design for a storage case lid, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top perspective view of a storage case lid in a closed position.

FIG. 2 is an enlarged perspective view of the slot, shown for ease of illustration.

FIG. 3 is a top perspective view of the storage case lid in an open position; and,

FIG. 4 is a perspective view of the underside of the lid with the slot thereof.

The broken lines depict portions of the storage case that form no part of the claimed design. The masked portions surrounded by broken lines in the figures depict portions of the storage case lid that form no part of the claimed design.
